(57) **CLAIM**

The ornamental design for a buckle member for bags, as
shown and described.

DESCRIPTION

FIG. 1 is a perspective view of a buckle member for bags,
showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line 8-8 in FIG.
2; and

FIG. 9 is a perspective view of the buckle member for bags
shown in an exemplary environment; and,

FIG. 10 is a perspective view of the buckle member of FIG.
9 shown in use.

The broken lines in the drawings are directed to environmental
matter and form no part of the claimed design.

1 Claim, 6 Drawing Sheets
